RAIL OILING DEVICE

Filed Dec. 1, 1928

Fig. 1.

UNITED STATES PATENT OFFICE

EMIL GEORGE METZ, OF DUNSMUIR, CALIFORNIA

RAIL-OILING DEVICE

Application filed December 1, 1928. Serial No. 322,989.

The present invention relates to a device for oiling the rails of railway tracks.

The principal object of the invention is to provide a device operated by the passage of a train or car for supplying a limited quantity of oil to the inner edge of the head of the rail for the purpose of lubricating said rail and the flanges of the wheels passing over it. A second object of the invention is to provide a device which needs no attention other than occasional filling of an oil reservoir. A third object is to provide in such a device means for regulating the amount of oil delivered to the rail upon the passage of each wheel or train. Still further objects and advantages of the invention will become apparent from the following description which should be read with the understanding that the form, construction, and arrangement of the several parts may be varied within the limits of the claims hereto appended without departing from the spirit of the invention.

The preferred embodiment of the invention will now be described with reference to the accompanying drawings which are partially diagrammatic in character, and in which—

Fig. 1 is a transverse section of a device embodying the invention, and

Fig. 2 is a sectional plan taken on the line 2—2 of Fig. 1 and enlarged.

In the drawings the reference numeral 3 designates a railway rail. The lubricant is supplied to the inner corner 4 of the head of said rail through a passage 5 extending through said head and communicating with a pipe 6. A supply of lubricant in a fluid state is contained in a reservoir 7. A piston 8 is closely fitted within said reservoir and rests upon the surface of the lubricant (not shown). A weight 9 is carried by the piston 8 for the purpose of applying pressure to the lubricant.

A pipe 10 leads from the bottom of the reservoir 7 to a valve chamber 11, said chamber being formed as a cylinder in which is a slidable piston 12. The piston 12 is secured upon a stem 13, the lower end of which carries a valve head 14 controlling the outlet of

the chamber 11 into the tube 6. The piston 12 is provided with ports 15 shown in Figs. 1 and 2. The stem 13 extends through suitable packing 16 in the upper end of the chamber 11 and is connected with a rocking arm 17 whose outer end 18 is positioned adjacent the head of the rail 3 and adapted to be depressed by a wheel passing along said rail.

When the lever 17 is rocked by the contact of a wheel with its end 18, the valve stem 13 is raised and the valve 14 is opened. The lubricant thereupon flows from the reservoir 7 through the pipe 10, the chamber 11, the ports 15 of the piston 12, the valve 14 and the pipe 6 to the outlet at the edge of the rail head. The pressure of the lubricant above the piston 12, which pressure is produced either by the height of the column of lubricant in the pipe 10 and the reservoir 7, or by the weight 9 upon the reservoir piston 8, or by a combination of both said forces, aided by the weight of the piston 12, stem 13, or lever 17, causes the valve piston 12 to descend and close the valve as soon as the wheel has passed the lever 17. The speed with which the piston 12 and valve 14 descend determines the duration of opening of the valve and depends upon the aggregate area of the ports 15 and the pressure of the lubricant above said piston 12. The chamber 11 and piston 12 act as a dashpot to retard the closing of the valve, and such dashpot effect can be regulated by varying the pressure of the lubricant or by changing the area of the ports 15 in said piston 12.

It will be seen that the device is simple and requires no attention other than occasional replenishing of the lubricant in the reservoir 7, and that it may be adjusted to deliver whatever amount of lubricant may be necessary properly to lubricate the rail and the flanges of the wheels passing over it.

I claim:—

A rail oiling device comprising a reservoir adapted to contain a supply of lubricant, a conduit connecting said reservoir with the rail, a cylinder included in said conduit, a piston operable in said cylinder adapted to partially restrict the flow of lubricant there-

through, a valve connected with said piston for closing said conduit, and means operated by the passage of a wheel along said rail for moving said piston against the flow of 5 lubricant in said cylinder to open said valve.

In testimony whereof I have signed my name to this specification.

EMIL GEORGE METZ.
